UNITED STATES PATENT OFFICE

154,866

DESIGN FOR A GAME BOARD

Merrell F. Miller, Oakland, Calif., assignor to The
Merrell Company, Oakland, Calif., a firm

Application November 7, 1947, Serial No. 142,391

Term of patent 7 years

(Cl. D34—5)

To all whom it may concern:

Be it known that I, Merrell F. Miller, a citizen of the United States and a resident of Oakland, county of Alameda and State of California, have invented a new, original, and ornamental Design for a Game Board, of which the following is a specification, reference being had to the accompanying drawing, forming part thereof.

I claim:

The ornamental design for a game board, substantially as shown.

MERRELL F. MILLER.
